REFRIGERATOR DOOR

Filed Nov. 16, 1929

UNITED STATES PATENT OFFICE

ERNEST HENRY NORWOOD, OF ST. PETERSBURG, FLORIDA

REFRIGERATOR DOOR

Application filed November 16, 1929. Serial No. 407,723.

This invention relates to improvements in doors designed especially for use in refrigerators.

The primary object of the present invention is to provide a refrigerator door having associated therewith means whereby the escape of cold air from the refrigerator when the door is opened, may be prevented.

Another object of the invention is to provide a refrigerator door having associated therewith a device which in addition to acting to prevent the escape of air from the refrigerator when the door is opened will act as a brace and support for the door so that the same, mounted to swing outwardly on horizontal hinges, may be used as a shelf or support for articles as the same are being removed or placed in the refrigerator.

The invention broadly contemplates the provision of a door secured on a hinge extending transversely of the refrigerator so that it may swing in a vertical plane, having secured to each side thereof a metal plate conforming in design to substantially a quarter 25 of a circle. One straight edge of each plate is secured to one side of the door while the other straight edge which has a lateral flange integral therewith is disposed in a slot in the body of the refrigerator and moves in and out 30 of the slot as the door is opened or closed, the flange engaging one side of the slot to prevent the door swinging down below a substantial horizontal position.

The invention will be best understood from 35 a consideration of the following detailed description taken in connection with the accompanying drawings forming part of this specification, with the understanding, however, that the invention is not confined to any strict 40 conformity with the showing of the drawings but may be changed or modified so long as such changes or modifications mark no material departure from the salient features of the invention as expressed in the appended 45 claims.

In the drawings:—

Figure 1 is a view in front elevation of a refrigerator equipped with the door and shield embodying the present invention.

Figure 2 is a vertical sectional view through

one side of a door opening showing the shield receiving recess therein.

Figure 3 is a view in horizontal section through one side of the refrigerator with the door in open position. 55

Figure 4 is a detailed perspective view of one of the quadrant plates or shields.

Referring more particularly to the drawings wherein like numerals of reference indicate corresponding parts throughout the 60 several views, the numeral 1 indicates generally a refrigerator of any conventional type in which the front is provided with transverse openings 2 leading to the interior thereof. 65

Closing each of the openings 2 is a door 3 which is mounted upon the hinge 4 which extends transversely of the lower part of the door opening so that the door swings in a vertical plane when opened or closed. 70

At each side of each door opening a vertical slot 5 is formed which leads into a recess 6 in the wall of the refrigerator, the recess being of slightly greater width than the opening or slot 5 thus forming the shoulder 7. 75

To each end or side of each door is secured one straight edge of a quadrant plate 8 the radius of which is substantially equal to the height of the slot 5. The other straight edge 80 of the plate 8 as shown in Figure 3 extends through the slot 5 into the recess 6 and has formed integral therewith the right angularly projecting flange 9. As shown the flange 9 abuts the shoulder 7 when the refrigerator 85 door is swung open so that the door is stopped in a horizontal position. This makes it possible to use the door as a supporting structure before the opening of the refrigerator and in addition the plate 8 at each end of the 90 door prevents the cold air from the refrigerator flowing out and over the ends of the door. This is particularly true when the door is opened only slightly as it is well known that cold air drops and it will thus 95 be seen that it cannot escape from the refrigerator when the door is opened in this manner.

In order to further prevent the escape of cold air when the door is opened a hinge 10 100

is employed which extends entirely across the lower edge of the door and door opening, this hinge being of the type commonly employed in pianos.

5 From the foregoing it will be seen that a refrigerator equipped with doors of the type herein described will be much more economical than those of the type where the doors are swung open or if they have doors which 10 swing downwardly where they are not equipped with the end plates or quadrants shown and described in connection with the present invention.

Having thus described my invention, what 15 I claim is:-

1. The combination with a refrigerator having a door opening, of a door having shoulders about its inner face, a hinge extending transversely of the refrigerator and 20 connecting the door thereto to swing in a vertical plane, said hinge acting to close the opening between the lower edge of the door and the refrigerator, said refrigerator body at each side of the door opening having a recess formed therein, a quadrant plate at each end of the door having one straight edge secured thereto and having the other straight edge permanently within said recess, said 25 plate being adapted to substantially completely enter the recess when the door is closed, said opening having abutment shoulders engaged by the door shoulders, those abutment shoulders adjacent the recesses being upon the inner sides of the recesses, and 30 means for preventing the complete removal of the plate from the recess.

2. The combination with a refrigerator having a door opening, of a door, a hinge extending transversely of the refrigerator and 40 connecting the door thereto to swing in a vertical plane, said hinge acting to close the opening between the lower edge of the door and the refrigerator, said refrigerator body at each side of the door opening having a recess formed therein, a quadrant plate at each end of the door having one straight edge secured thereto and having the other straight edge permanently within said recess, said 45 plate being adapted to substantially completely enter the recess when the door is closed, means to provide a shoulder within the recess, and a flange extending laterally from that edge of each plate within the recess adapted to abut the shoulder to prevent 50 complete removal of the plate from the recess.

In testimony whereof I hereunto affix my signature.

ERNEST HENRY NORWOOD.
